UNITED STATES PATENT OFFICE.

JOHN PHILIP HILL, OF BALTIMORE, MARYLAND.

TOOTH BRUSH AND POWDER RECEPTACLE.

No. 853,549.

Specification of Letters Patent.

Patented May 14, 1907.

Application filed August 27, 1906. Serial No. 332,193.

To all whom it may concern:

Be it known that I, JOHN PHILIP HILL, a citizen of the United States of America, and a resident of Baltimore city, and State of Maryland, have invented certain new and useful Improvements in Tooth Brush and Powder Receptacles, of which the following is a specification.

My invention relates to a combined receptacle for holding tooth powder and a tooth brush, and is designed for the purpose of retaining the tooth powder in a convenient and dry form and always ready for use, and the tooth brush protected, clean, free from dust, and at the same time ventilated and in such a form that the tooth powder and brush may be carried in a traveling bag with convenience and cleanliness.

Referring to the drawings, Figure 1 is a perspective view of my receptacle. Fig. 2 is a vertical, longitudinal section of the receptacle. Fig. 3 is a vertical transverse section, and Fig. 4 is a perspective view of the tooth brush receptacle.

Referring to the drawings,—1 is a box having an interior compartment (2) and an opening in its top (3) and another in its end (4); 5 is a draw or slide open for the greater part of its length but having a closed pocket (6) at one end in which there are ventilating holes. This slide is of a size suitable to hold a tooth brush. On the interior of the box (2) there is a partition (7) occupying a part of the length of the box and upon which the draw (5) slides. This partition might be substituted by guides upon the sides of the box, which would serve much the same purpose.

The tooth brush is placed in the drawer (5) which is inserted in the open end (4) of the box (2) and when pushed home will close the aperture (3) and thus hold the tooth powder safely in the lower compartment of the box. When the device is to be used the draw (5) may be withdrawn from the box by grasping its outer edges through slots (8). The withdrawal of the draw (5) will remove it from

below the aperture (3). The brush may then be taken from the draw and inserted through the aperture (3) and a suitable quantity of powder obtained.

My mechanism is cheap to construct, sanitary, cleanly, secure, holds tooth powder in a manner which makes it easily accessible, ventilates a wet tooth brush and yet holds it free from contact with clothing in a traveling bag.

I have described my invention as applicable to a tooth brush and tooth powder, but it will be understood that the same mechanism may be employed for other purposes.

Having thus described my invention, what I claim and desire to secure by Letters Patent is:—

1. In a tooth brush and powder holder, the combination of an elongated box adapted to hold tooth powder, having an opening in one side near the end, a longitudinal partition parallel to the side in which is the opening and extending to near the edge of the opening, thus leaving two registering openings opposite each other, with a toothbrush holder consisting of an elongated box having a closed pocket at one end adapted to hold a toothbrush and to be inserted within the toothpowder box above the partition and when so inserted will close both the outer and inner apertures of the box.

2. In a tooth brush holder, the combination of a powder receptacle having an aperture in one end for insertion of a brush, a brush holder consisting of a drawer as long as the powder receptacle and having a pocket in one end, means in the receptacle for holding the drawer in place, the pocket portion of said drawer being adapted to close the aperture to the powder receptacle when in place.

Signed by me at Baltimore city & State of Maryland this 20th day of August 1906.

JOHN PHILIP HILL.
